US0D1028382S

(12) **United States Design Patent** (10) **Patent No.:** **US D1,028,382 S**
(45) **Date of Patent:** **** May 21, 2024**

(54) **SNAP-TOGETHER HORSESHOE ASSEMBLY**

(71) Applicant: **Equine Hoof Innovations, LLC**,
Highlands, NC (US)

(72) Inventor: **Susan Blair**, Highlands, NC (US)

(73) Assignee: **EQUINE HOOF INNOVATIONS,
LLC**, Highlands, NC (US)

(**) Term: **15 Years**

(21) Appl. No.: **29/760,167**

(22) Filed: **Nov. 30, 2020**

(51) **LOC (14) Cl.** **30-01**

(52) **U.S. Cl.**

USPC **D30/147**

(57) **CLAIM**

The ornamental design for a snap-together horseshoe assembly, as shown and described.

DESCRIPTION

FIG. 1 is a top, front perspective view of a snap-together horseshoe assembly, shown exploded for clarity of disclosure;

FIG. 2 is a rear, bottom perspective view thereof;

FIG. 3 is a rear elevation view of the snap-together horseshoe assembly, shown assembled;

FIG. 4 is a front elevation view thereof;

FIG. 5 is a bottom plan view thereof;

FIG. 6 is a top plan view thereof;

FIG. 7 is a right side elevation view thereof;

FIG. 8 is a left side elevation view thereof;

FIG. 9 is a top front perspective view thereof;

FIG. 10 is a top rear perspective view thereof;

FIG. 11 is a bottom front perspective view thereof; and,

FIG. 12 is a bottom rear perspective view thereof.

The broken lines in the drawings depict portions of the snap-together horseshoe assembly that form no part of the claimed design.

1 Claim, 10 Drawing Sheets
